UNITED STATES PATENT OFFICE.

EDWARD H. WEATHERHEAD, OF CLEVELAND HEIGHTS, AND HAL T. PATTON, OF CLEVELAND, OHIO, ASSIGNORS TO THE BISHOP AND BABCOCK COMPANY, OF CLEVELAND, OHIO, A CORPORATION OF OHIO.

DAMPER REGULATOR.

Application filed September 18, 1919. Serial No. 324,405.

To all whom it may concern:

Be it known that we, EDWARD H. WEATHERHEAD and HAL T. PATTON, citizens of the United States, and residents of Cleveland 5 Heights, county of Cuyahoga, State of Ohio, and Cleveland, county of Cuyahoga, and State of Ohio, respectively, have jointly invented a new and useful Improvement in Damper Regulators, of which the following 10 is a specification, the principle of the invention being herein explained and the best mode in which we have contemplated applying that principle, so as to distinguish it from other inventions.

15 The present improvements, relating, as indicated to damper regulators, are more particularly directed to an improved means for permitting the fluid pressure which operates the damper to escape from the valve or casing 20 in case of a sudden increase to the pressure above the normal limits. The present damper regulator is of the type employing a metallic bellows of high elasticity and consequently having a relatively thin wall. 25 Such a bellows is extremely flexible and elastic within certain limits, and is so easily actuated that an increase of pressure beyond that usually occurring will expand the bellows beyond the elastic limit of the material, 30 and many times rupture the corrugated walls of the bellows. It is to prevent this action that the present improvements are intended. To the accomplishment of the foregoing and related ends, said invention, 35 then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

40 Fig. 1 as a transverse vertical section through our improved regulator; Fig. 2 is a plan view of the same; and Fig. 3 is an enlarged view of one of the valves shown in Fig. 1.

45 In Figs. 1 and 2 there is shown a disk-like cylindrical casing 1, having an opening 2 formed centrally in its lower surface and there provided with a downwardly extend-

ing threaded boss 3 disposed about such opening 2 and adapted to be attached to a fluid pressure conduit, such as a steam pipe, extending upwardly from a boiler or steam line. Upon the upper surface of the casing 1 is pivotally mounted a lever 4 provided with adjustable weights 5 and 6 upon either side of its axis and adapted for connection to damper-operating chains, (not shown) at either end. It is usual in such constructions to operate two dampers or valves simultaneously, one being closed while the other is opened. Extending downwardly from the lever 4 is a rod 9, which is pivotally attached to a lever 8, and which passes through an opening 10 formed in the top of the casing 1, where it is attached to the upper plate 11 of the bellows. The bellows consist of the upper plate 11, to which is integrally attached the upper edge of a corrugated metallic bellows 12, which is similarly integrally attached to the plate 7 at its other end, which plate forms the bottom of the casing 1. The lower end of the bellows is thus fixed to the casing, while the upper end, upon expansion of the bellows, serves to lift the plate 11 and the rod 9, and thus swing the damper regulating bar 4 about its axis. The operation of a regulator of this type is controlled by the pressure of the steam in the bellows, the interior of the bellows being always in connection with the steam line 80 from the boiler. If the pressure is raised the bellows expands, swinging the lever 4 and lifting one end, while lowering the other. On a decrease in the pressure the opposite action is secured, the bellows being contracted, and the rod 4 swung in the opposite direction.

45 Our improvements relates to a means for preventing injury to the bellows upon an unusual rise in pressure, and comprises means 95 for closing the bellows to the admission of steam after a predetermined pressure exists in the bellows chamber, and at the same time allowing the pressure existing in the bellows chamber to escape through the top 100 of the bellows. Extending downwardly from the plate 11 of the bellows is an open chamber 13, within which is mounted a tapered valve 14 and a rod 15 attached thereto. Between the end of the open chamber 13 and 105 the valve 14 is mounted a spring 16, which

normally maintains the valve 14 against its seat formed in the end of the rod 9, and closes communication with the atmosphere through the passages 17 and 18. The rod 5 15 extends vertically through the bellows and into the opening formed in the boss 3, where it carries a valve 20 adapted to engage against a seat 21. The seat 21 is conveniently formed of a threaded and flanged 10 collar 22, of which the flange abuts against the upper surface of the plate 2, while the threading engages with a nut or collar 23 below the plate, thus locking the collar in position. As the lower end or plate 24 of 15 the bellows is integrally engaged around its outer edge with the plate 2, the locking action of the flange on the collar 22, when engaged with the nut 23, serves to make a steam-tight joint between the bottom wall 20 of the bellows and the plate 2 at the opening through which passes the rod 15. The lower plate of the bellows is of course apertured to the same size as the opening 2.

During the normal range of expansion 25 of the bellows the valve 20 is never seated, while the valve 14 is maintained on its seat to close the upper wall of the bellows. Thus, for any normal range of steam pressure the bellows will act in the usual manner, or upon any increase of pressure in the 30 bellows above a predetermined amount, the bellows, when expanded an unusual distance, will pull the valve 20 onto its seat and thus prevent the further admission of steam. The rod 15 is then held while the 35 steam pressure in the bellows acts against the entire surface of the plate 11 to move this plate upward, and at the same time move the rod 9 away from the valve 14. This 40 action will open the passages 17 and 18 to the interior of the bellows and permit the escape of the high steam pressure to the atmosphere through the passages 17 and 18. Ordinarily there should be no such further 45 travel of the upper plate of the bellows, once the valve 20 is closed, but in actual practice this valve sometimes becomes slightly scaled or corroded so that it will not seat perfectly and some additional fluid 50 pressure will leak past it and increase the pressure in the bellows. If the steam pressure in the bellows were allowed to increase it would of course rupture the bellows, but this is prevented by the opening of the 55 valve 14 if the increase is continued. After the steam pressure has been discharged from the bellows it will contract, bringing the tube 9 again into engagement with the valve 14, and, upon further movement, re-opening 60 the valve 20 and permitting the bellows to act in the usual manner.

Other modes of applying the principle of our invention may be employed instead of the one explained, change being made 65 as regards the mechanism herein disclosed,

provided the means stated by any of the following claims or the equivalent of such stated means be employed.

We therefore particularly point out and distinctly claim as our invention:—

1. In a damper regulator, the combination of a casing, a cylindrical bellows member mounted therein and having one end fixed to said casing, means adapted to admit fluid pressure to said bellows, damper 75 controlling means operable upon expansion and contraction of said bellows under the influence of such fluid pressure, valve means operated upon predetermined expansion of said bellows to close the same 80 against further admission of fluid pressure, and other valve means operable upon further expansion of said bellows to open the same to the atmosphere.

2. In a damper regulator, the combination 85 of a casing, a cylindrical bellows member mounted therein and having one end fixed to said casing, means adapted to admit fluid pressure to said bellows, damper controlling means operable upon expansion 90 and contraction of said bellows under the influence of such fluid pressure, valve means operated upon predetermined expansion of said bellows to close the same against further admission of fluid pressure, 95 and a valve normally closing a port in the movable end wall of said bellows, said valve having a predetermined travel with respect to said other end of said bellows, whereby expansion of said bellows beyond 100 a predetermined amount will open said last-named valve.

3. In a damper regulator, the combination 105 of a casing, a cylindrical diaphragm member mounted therein and having one end fixed to said casing, means adapted to admit fluid pressure to said diaphragm, damper controlling means operable upon expansion 110 and contraction of said diaphragm under the influence of such fluid pressure, valve means operated upon predetermined expansion of said diaphragm to close the same against further admission of fluid pressure, and other valve means operable upon further expansion of said diaphragm to open 115 the same to the atmosphere.

4. In a damper regulator, the combination 120 of a casing, a cylindrical diaphragm member mounted therein and having one end fixed to said casing, means adapted to admit fluid pressure to said diaphragm, damper controlling means operable upon expansion 125 and contraction of said diaphragm under the influence of such fluid pressure, valve means operated upon predetermined expansion of said diaphragm to close the same against further admission of fluid pressure, and a valve normally closing a port in the movable end wall of said diaphragm, said valve having a predetermined travel with 130

- respect to said other end of said diaphragm, whereby expansion of said diaphragm beyond a predetermined amount will open said last-named valve.
5. In a fluid pressure regulator, the combination of a casing, a diaphragm member mounted therein and having one edge fixed to said casing, means adapted to admit fluid pressure to said diaphragm, fluid pressure controlling means operable upon movement of said diaphragm under influence of said fluid pressure, valve means operated upon predetermined expansion of said dia-
- phragm to close the same against passage of said fluid, and a valve normally closing 15 a port in said diaphragm, said valve having a predetermined travel with reference to said support whereby an excess movement of the diaphragm beyond a predetermined limit operates to open said valve port in said 20 diaphragm to release the pressure on same.
- Signed by us, this 11th day of September, 1919.

EDWARD H. WEATHERHEAD.
HAL T. PATTON.
